UNITED STATES PATENT OFFICE.

GROSVENOR N. ALLEN, OF ONEIDA, NEW YORK, ASSIGNOR TO ONEIDA COMMUNITY, LIMITED, OF ONEIDA, NEW YORK, A CORPORATION OF NEW YORK.

DESIGN FOR A HANDLE FOR SPOONS, FORKS, OR SIMILAR ARTICLES.

41,783.

Specification for Design.

Patented Sept. 19, 1911.

Application filed April 17, 1911. Serial No. 621,709. Term of patent 14 years.

To all whom it may concern:

Be it known that I, GROSVENOR N. ALLEN, a citizen of the United States, residing at the city of Oneida, in the county of Madison, State of New York, have invented a new, original, and ornamental Design for Handles for Spoons, Forks, or Similar Articles, of which the following is a specification, reference being had to the accompanying drawing, forming a part thereof, in which the design consists in the form and ornamentation of the handle portion of a spoon.

The essential feature of this design consists in the ornamentation of the upper face of the outer end of the handle as shown and confined between the marginal beads or raised portions.

What I claim is:

The ornamental design for a handle for spoons, forks or similar articles as shown and described.

GROSVENOR N. ALLEN.
